UNITED STATES PATENT OFFICE.

HARLEY M. CLEARWATER, OF TROY, NEW YORK, ASSIGNOR, BY MESNE ASSIGNMENTS,
TO REECE FOLDING MACHINE COMPANY, OF BOSTON, MASSACHUSETTS, A CORPOR-
ATION OF MAINE.

BLANK-FOLDING MACHINE.

1,149,185.

Specification of Letters Patent.

Patented Aug. 10, 1915.

Application filed April 19, 1913. Serial No. 762,163.

To all whom it may concern:

Be it known that I, HARLEY M. CLEARWATER, a citizen of the United States, residing at Troy, in the county of Rensselaer and State of New York, have invented certain new and useful Improvements in Blank-Folding Machines, of which the following is a full, clear, and exact description.

This invention relates to machines for folding or "turning" blanks for the manufacture of collars, cuffs, and the like, and pertains more particularly to machines having expansible and collapsible templets over the edges of which the edges of the blanks are folded.

The chief object of the invention is to provide improved means, of simple character, for expanding and collapsing the die or templet.

To this and other ends the invention consists in the novel features of construction and combinations of elements hereafter described; and more particularly set forth in the appended claims.

A convenient and effective embodiment of the invention as applied to the blank-folding machine illustrated in the patent of Joseph H. Ramsey, John Temple and myself; No. 1,043,722, is illustrated in the accompanying drawings, but it is to be understood that the invention is not limited to use with the machine mentioned.

Referring now to the drawings, Figure 1 is a front view showing the invention embodied in a folding machine. Fig. 2 is a detail side view partly in vertical section. Fig. 3 is a detail plan view of the machine with a portion at the left broken away. Fig. 4 is a detail plan view of the templet-actuating devices, the actuating lever being shown only in part. Figs. 5 and 6 are detail side views showing the swinging head and templet-actuating devices in different operative positions.

The bed of the machine, upon which the blank is laid, is designated by 10, and is capable of limited vertical movement in the table 11; being for this purpose connected to a pair of toggles 12, 13. The lower links of these toggles are fixed to a transverse rock shaft 14, journaled in brackets 15 depending from the table 11, and fixed to the same shaft is an arm 16 cooperating with a face cam 17 fixed on the cam shaft 18. The contour of the cam is

such that as the cam shaft rotates, the toggles will be alternately buckled and straightened, thereby lowering and raising the bed 10, as will be readily understood.

At the back of the machine is a shaft 19, on which is a pair of forwardly extending arms 20, carrying at their forward end a supporting plate or head 21 carrying on its underside a plurality of shiftable angle-members 22 having depending legs 23 to which the four-part die or templet 24 is attached by means of the vertical plates 25. The members 22 are provided with pins 26, extending upwardly through slots 27 in the plate 21 and connected, above the plate, to the levers 28, 29, 30 . . . 35, fulcrumed on the top of the said plate. Levers 29 and 30 are geared together, as shown, so that when either is rocked the other must swing to an equal extent but in the opposite direction, and levers 33 and 34 are similarly connected for the same purpose. It will therefore be seen that when the levers 29, 30, and 33, 34 are rocked the four parts or sections will be shifted in and out in diagonal lines, thereby expanding and collapsing the templet.

Pivoted on the head or plate 21 at the center thereof is a disk 35^a connected by links 35^b and 35^c to the levers 29 and 33, said links being pivoted to the disk on opposite sides of its pivot 35^a, so that when the disk is given a partial rotation the levers 28, 29, . . . 35 are actuated and the templet 24 is collapsed and expanded, as described in the preceding paragraph. Encircling the disk is a split collar 35^e, which may be rotatively adjusted on the disk and then secured in adjusted position by a bolt 35^f. On the right side of the collar, as seen from the position of the operator as he stands facing the machine, is a notch or recess 35^g, for the purpose explained hereinafter.

Encircling the legs 25 of the die or templet 24 (which, when expanded, conforms to the size and contour of the finished blank) is a presser 36 carried by a frame 37, slideable vertically on rods 38 depending from the plate or head 21. Coil springs 39, encircling the rods 38, normally hold the frame presser above the templet, as shown, but permit the presser to be drawn down at the proper time into contact with the folded edges of the blank. The presser itself has substantially the contour of the

folded blank, its bottom edges preferably being wide enough to extend outwardly beyond the fold and inwardly beyond the internal edges of the blank, and is heated in any convenient manner, as by the means described in the aforesaid Patent No. 1,043,722.

To seat the presser 36 on the folded edges of the blank the frame 37 is provided at its ends with lugs 40, 41, having beveled upper edges to coöperate with the correspondingly beveled under-edges of the inwardly turned upper ends of a pair of vertical cam levers 42, 43, fulcrumed at 44, 45 below the table 11 and extending up through suitable apertures therein. Initially the levers are in their outer positions, wholly disconnected from the presser frame 37; but at the proper time they are swung in and eventually engage the lugs 40, 41 and cam the frame down, thereby seating the presser on the folded blank-edges. To rock the levers in the manner just described their lower ends terminating in suitable anti-friction rollers 46, 47, extend into coöperation with a pair of suitable cams 48, 49 on the cam shaft 18; so that as the shaft rotates, the levers will be swung in and out.

The arms 20, which, as before stated, carry the head or support 21, are swung up and down about the axis of shaft 19, to carry the head toward and from the bed 10, by an arm 50, suitably connected with said arms. To rock the arm 50 it is pivoted to a downwardly and favorably extending link 51, the forked lower end of which straddles the cam shaft 18 and has a stud 52 extending laterally into a suitable face cam 53 fixed on said shaft, so that as the shaft rotates the cam 53 the link will be reciprocated and the arm 50 rocked accordingly.

The parts so far described are found in the machine illustrated in the prior Patent No. 1,043,722, above referred to, and the operation, briefly stated, is as follows: The head carrying the templet 24 and presser 36 being raised, the blank to be folded, composed of one or more layers of cloth cut to the proper shape, is laid upon the bed 10, after which the head descends and is seated in expanded position on the blank. Suitable infolders, not shown, then move in and fold the edges of the blank over the edges of the templet. As soon as the infolders reach their inner positions they are retracted, and at the same time the templet collapses. While the infolders and the templet are being freed from the folded blank-edges the levers or arms 42, 43 cam the presser down upon the blank-edges, and when the presser is seated the cam 17 straightens the slightly buckled toggles 12, 13, thereby raising the bed 10 and pressing the folded blank firmly against the presser.

After the bed has been held momentarily

in raised position, to give the folded blank edges a sharp and permanent crease, the cam 17 buckles the toggles slightly, the levers 42, 43 swing out to free the presser, whose springs 39 immediately raise it clear of the blank, and the cam 53, acting through the link 51, arm 50, and arms 20, raise the head 21, which carries the templet 24 and presser 36. The folded and pressed blank is then removed from the bed and an unfolded blank is placed in position, after which the cycle described is repeated. It is to be understood that any convenient means, not shown, may be used to rotate the cam shaft 18 at a suitable speed.

My invention in its present embodiment has to do with the actuation of the disk 35^a to expand and collapse the templet, and for this purpose I provide a lever 60, fulcrumed on a plate or arm 61 rigidly fixed to the right-hand arm 20 and extending rightwardly past the end of the head or plate 21. The lever 60 has on its inner end an anti-friction roller 62 engaging the notch 35^a in the collar 35^e, so that as the lever is moved on its fulcrum the disk 35 is rocked and the templet is expanded and contracted. The fulcrum 63 is adjustable in longitudinal slots in the lever 60 and bracket 61, to vary or regulate the throw of the inner end of the lever and so vary or regulate the in-and-out movements of the templet sections, as will be readily understood. The outer arm of the lever is depressed into a plane a slight distance above the top of the lever 43 and its outer end carries an anti-friction roller 64. Below this roller is a plate 65, securely fixed to the right hand edge of the table 11 and having at its rear an upwardly extending stationary finger 66. At its front the said plate has a guide and stop finger 67, which is arc-shaped and concentric with the shaft 19. Across the two fingers on the outside thereof is a bridge 68, on which is pivoted an upwardly extending one-way swinging stop-switch or cam-member 69, normally held against the stop finger 67 by a spring 70. On top of one fork of the lever 43 is a cap 71, on which is an anti-friction roller 72 to coöperate at the appropriate time with an inclined cam edge 73 on the depressed portion of the outer arm of lever 60.

As the head 21 descends with the templet collapsed, the roller 64, swinging in an arc parallel to the finger 67 and inclined edge 74 on the finger 66, passes between the fingers and strikes the vertical rear edge of the switch 69, as indicated in dotted lines in Fig. 5. The outer end of the lever 60 is then compelled to take a vertical rectilinear path while its fulcrum continues to move in an inclined path parallel with the finger 67, thereby causing the lever to swing counter-clockwise, as seen from above. This expands the templet, the expansion of the lat-

ter being completed just before it reaches the unfolded blank on the bed 10 and just as the roller 64 escapes from the bottom of the switch 69, after which the roller passes 5 idly along the curved edge 75 concentric with the shaft 19. At the proper time the lever 43 swings in, as explained above, but before it depresses the presser into contact with the folded blank the roller 72, on the 10 upper end of the lever engages the inclined cam-edge 73 on the lever 60, as shown in Fig. 5, and swings the latter clockwise (as seen from above), thereby collapsing the templet and moving the roller 64 over to 15 ward the inner edge of the finger 67. This collapsing of the templet by means of the same lever which applies pressure is effected during the time that the templet is upon the blank on the bed or support and after the 20 infolders have turned in the blank edges previous to pressing, so that the edges are first folded, then freed from the templet and finally pressed. The presser is now cammed down upon the folded blank, which 25 is free from the collapsed templet and the retracted infolders. The pressing having been completed, the lever 43 swings back to its outer or initial position and the head 21 is raised. This carries the roller 64 up- 30 wardly in a curved path concentric with the inner edge of the finger 67, the switch 69 swinging rearwardly (as in Fig. 6) to permit the roller to pass, and snapping back to its normal position against the stop-finger 35 or brace 67 as soon as it is free of the roller. The parts are thus restored to their initial positions.

From the foregoing it will be seen that my invention in its preferred form dispenses with all costly rotary cams whose sole function is to expand and collapse the templet, and instead makes use of a fixed cam and one of the members which co-operate with the pressing devices. I also eliminate the train of gears heretofore employed to transmit motion from the main cam shaft to the templet sections, thereby further simplifying the machine. If desirable, reliance may be placed entirely upon the 40 presser 36, without upward movement of the bed 10, to press the folded blank, in which case it is only necessary to remove the toggles 12, 13, and fasten the bed in its upper position by any convenient means, not shown.

It will also be seen that the invention comprises a novel mode of controlling the expansion and contraction of the templet, also a novel specific mode of expanding the templet previous to folding and also a novel specific mode of contracting the templet after infolding and before pressing. The machine, which is adapted for infolding the edges of blanks for collars or analogous articles, may be said to comprise the combina- 50

tion of the bed or support 10 for blanks, the expandible and contractible templet, the upwardly and downwardly swingable templet carrier 20 adapted to accurately position the templet upon the blanks on the support, 70 mechanism carried with the templet adapted to effect expansion and contraction thereof, said mechanism including a movable projection or lever 60, infolders for infolding blank edges over the templet edges, 75 means for applying a creasing pressure upon the folds of the blanks on the support, namely, by forcing a presser toward the folds, a passive contact or cam device 65 which operates through the positioning descent of the templet to actuate the templet mechanism for expanding the templet, such contact being mounted in the machine in the path of the projection or lever 60 for co-operation thereof but wholly disconnected 80 therefrom when the templet is fully elevated, together with active connections 71 which are independent of the passive contact and are operated by the pressure applying means for actuating the templet 85 mechanism so as to contract the templet before the pressing is effected; and the contact 65 and the connections 71 being such as to permit the contractible templet to rise before the pressure applying means resumes its original condition. The parts are all harmoniously connected so that from a single shaft they are automatically operated with the following timing: The templet is caused to descend and to be positioned upon 100 the blanks in expanded condition; afterward, and when the folds are formed, the presser is applied, contracting the templet and creasing the folds; the contracted templet is lifted to original position; and finally the pressing means is restored to original condition. 105

It is to be understood that the invention is not limited to the structure herein specifically described, but can be embodied in other forms without departure from its proper spirit and scope as defined by the appended claims.

What I claim is:

1. In a machine for infolding the edges of blanks for collars or analogous articles, the combination of a support for blanks, an expandible and contractible templet, an upwardly and downwardly movable templet carrier adapted to accurately position the templet upon the blanks on the support, expanding and contracting mechanism carried with said templet, means for infolding blank edges over templet edges, means for applying creasing pressure upon the folds of the blanks on the support, a passive device operating through the positioning descent of the templet to actuate said mechanism to expand the templet, and active connections operated by said pressure applying 115
- 120
- 125
- 130

means for actuating said mechanism to contract the templet.

2. In a machine for infolding the edges of blanks for collars or analogous articles, the combination of a support for blanks, an expandable and contractible templet, an upwardly and downwardly movable templet carrier adapted to accurately position the templet upon the blanks on the support, expanding and contracting mechanism carried with said templet comprising a shiftable projection, means for infolding blank edges over templet edges, means for applying creasing pressure upon the folds of the blanks on the support, a passive device having a fixed location in the path of the descending projection and operating through the positioning descent of the templet to actuate said mechanism to expand the templet, and active connections operated by said pressure applying means for actuating said mechanism to contract the templet.

3. In a machine for infolding the edges of blanks for collars or analogous articles, the combination of a support for blanks, infolding means, an expandable and contractible templet, an upwardly and downwardly movable templet carrier adapted to accurately position the templet upon the blanks on the support, expanding and contracting mechanism carried with said templet comprising a shiftable projection, a passive device having a fixed location in the path of the descending projection and operating through the positioning descent of the templet to actuate said mechanism to expand the templet, and an active device for contracting the templet while positioned on said support.

4. In a machine for infolding the edges of blanks for collars or analogous articles, the combination of a support for blanks, an expandable and contractible templet, means for moving the templet up and down, including an upwardly and downwardly movable templet carrier adapted to accurately position the templet upon the blanks on the support, expanding and contracting mechanism carried with said templet, means for infolding blank edges over the templet edges, means for applying creasing pressure upon the folds of the blanks on the support, and active connections operated by said pressure applying means for actuating said mechanism to contract the templet on the support before the creasing of the blank is effected, said connections being independent of the fittings by which the templet is moved up and down.

5. In a machine for infolding the edges of blanks for collars or analogous articles, the combination of a support for blanks, an expandable and contractible templet, means for moving the templet up and down including an upwardly and downwardly movable

templet carrier adapted to accurately position the templet upon the blanks on the support, expanding and contracting mechanism carried with said templet, means for infolding blank edges over the templet edges, means for applying creasing pressure upon the folds of the blanks on the support, and active connections operated by said pressure applying means for actuating said mechanism to contract the templet on the support before the creasing of the blank is effected, said connections being independent of the fittings by which the templet is moved up and down and other means, independent of the pressure applying means for automatically effecting expansion of the templet prior to the operation of the folding means.

6. In a blank-folding machine, the combination of a support for the blank, a head movable vertically toward and from the support, an expandable and collapsible templet carried by the head, a laterally extending lever fulcrumed on the head and connected with the templet to expand and collapse the same, a pivoted cam-member in the path of the outer portion of the lever for engagement thereby, a stop against which the cam-member bears when engaged by the downwardly moving lever whereby such downward movement will actuate the lever in one direction, and means for moving the lever in the opposite direction after the lever has passed the cam-member.

7. In a blank-folding machine, the combination of a table, a head movable vertically toward and from the table, an expandable and collapsible templet carried by the head, a laterally extending lever carried by the head and connected with the templet to expand and collapse the same, a supporting device fixed at the side of the table and having front and rear fingers extending upwardly, a vertical cam-member pivoted between said fingers with its rear edge in the path of the outer end of the lever in its downward movement and its upper end bearing on the front finger, and means operating after the outer end of the lever has passed the cam-member to shift said outer end to the front of the cam-member.

8. In a blank-folding machine, the combination of a support for the blank, a head movable toward and from the support, an expandable and collapsible templet carried by the head, templet-expanding and collapsing mechanism carried by the head, means for causing the movement of the head toward the support to actuate said mechanism to expand the templet, a presser movable upon and carried by the head and normally spaced above the support when the head is at its nearest approach to the support, an actuating lever common to the said mechanism and the presser and co-operating

first with the former to collapse the templet and then with the presser to move the same toward the support.

9. In a blank-folding machine, the combination of a support for the blank, a head movable toward and from the support, an expansible and collapsible templet carried by the head, a lever carried by the head and connected with the templet to expand and collapse the same, said lever having a cam-edge, means for actuating the lever in one direction to expand the templet while the head is approaching the support, and means adapted to coöperate with the said cam-edge to actuate the lever in the opposite direction and collapse the templet.

10. In a blank-folding machine, the combination of a support for the blank, a head movable toward and from the support, an expansible and collapsible templet carried by the head, a templet-expanding and collapsing lever carried by the head, means to actuate the lever and expand the templet, a presser carried by the head, yielding means for holding the presser out of contact with the blank when the templet is seated on the blank, and means for moving the presser toward the support to seat the presser on the blank, said means including a lever coöperating first with the first named lever to actuate the same and collapse the templet and then with the presser to seat the same.

11. In a blank-folding machine, the combination of a support for the blank, a head movable vertically toward and from the support, an expansible and collapsible templet carried by the head and adapted to be seated on the blank, a laterally extending lever carried by the head and connected with the templet to expand and collapse the same and having an inclined cam-edge, means coöperating with the lever to expand the templet before the same is seated on the blank, a presser carried by the head and yieldingly held above the blank while the templet is seated on the latter, a lever movable toward and from the inclined cam-edge on the first-named lever to actuate the same and collapse the templet and thereafter to coöperate with the presser and depress the same.

12. In a blank-folding machine, the combination of a support, a head movable vertically relatively to the support, an expan-

sible and collapsible templet carried by the head, a templet-expanding and collapsing lever carried by the head and extending laterally therefrom; and means for actuating the lever to expand and collapse the templet, comprising a cam-member in the path of the outer portion of the lever as the same moves downwardly, a lever mounted at the side of the support to coöperate with the first lever, and means to actuate the second lever after the latter has passed the said cam-member.

13. In a blank-folding machine, the combination of a support for the blank, a head movable vertically toward and from the support, a templet-expanding and collapsing lever carried by the head and extending laterally therefrom; and means for actuating the lever, comprising a pivoted upwardly extending cam-member having its rear edge in the path of the outer end of the lever as the lever moves downward, a stop to prevent forward pivotal movement of the cam-member by the downwardly moving lever, a second lever at the side of the support to coöperate with the first named lever and actuate the same, and means for actuating the second lever after the first-named lever has passed the cam-member.

14. In a blank-folding machine, the combination of a support, a vertically movable head, an expansible and collapsible templet carried by the head, a templet-expanding and collapsing lever carried by the head and extending laterally therefrom, and having an inclined cam-edge, a pivoted cam-member in the path of the outer end of the lever, means to prevent pivotal movement of the cam-member by the lever in its downward movement, a lever pivoted at the side of the support to swing inwardly and outwardly and adapted to coöperate with the inclined cam-edge of the first-named lever, and means to swing the second lever into co-operation with said cam-edge after the outer end of the first lever has passed said cam-member.

In testimony whereof I affix my signature in the presence of two subscribing witnesses.

HARLEY M. CLEARWATER.
